UNITED STATES PATENT OFFICE.

JOHN J. TAGUE, OF BROOKLYN, NEW YORK.

PRESSURE-REDUCING VALVE.

1,231,966.

Specification of Letters Patent.

Patented July 3, 1917.

Application filed May 26, 1916. Serial No. 100,043.

To all whom it may concern:

Be it known that I, JOHN J. TAGUE, a citizen of the United States, residing at the borough of Brooklyn, city of New York, 5 in the county of Kings and State of New York, have invented certain new and useful Improvements in Pressure-Reducing Valves, of which the following is a specification.

My invention relates to water regulator valves in which the street main pressure must be reduced on one side of the valve and it is my object to construct a simple valve which will be mechanically strong, 10 simple in its operation and which will not easily get out of order, through which a maximum of water will flow, which can be easily regulated from the outside, in which the counter balance may be released to obtain full main pressure if desired and which 15 will be easily accessible for repairs.

In the drawing Figure 1 is a sectional view of the valve in closed position; Fig. 2 a top view and Fig. 3 a modified control device.

25 The valve comprises a casing 1 having the inlet chamber 2 and outlet chamber 3, divided by the valve seat 4. A cylinder 5 is located above the outlet and has its upper end in free communication therewith 30 through the passage 6. The upper part of the cylinder is slightly enlarged to facilitate removing and inserting the piston.

The stem 7 carries the valve 8 at its lower end and the piston 9 within the cylinder 35 with the copper bucket 10 below the piston. This valve stem 7 projects through the top of the casing and a counterbalance in the form of a spring 11 bears on the stem with the stirrup 12 holding the upper end. The 40 nuts 13 bearing on the bar 14 form means for adjusting the spring pressure.

In use the full main pressure of say 100 pounds enters the inlet chamber 2. If 40 pounds pressure is desired on the outlet side 45 the spring 11 is adjusted to counterbalance a 60 pound pressure. The main pressure will then raise the piston 9 allowing the water to enter the outlet chamber 3, passage 6 and upper part of the cylinder 5 until a 50 pressure of 40 pounds is exerted on top of the piston when the additional pressure of 60 pounds from the spring will close the valve and no more water can pass from the

inlet chamber to the outlet chamber until the pressure in the latter is reduced by 55 drawing off water when the piston will rise carrying the valve with it until the balance is reestablished when the valve will close.

In my valve the maximum volume of water will pass the valve when open owing 60 to its large size and full lift and when closed the full main pressure on the top of the valve holds it firmly on its seat to prevent slow leakage. The copper bucket 10 being at all times forced against the cylinder walls prevents grit and sand reaching 65 the piston and its packing and interfering with the smooth operation of the valve.

In use on fire extinguisher stand pipes it is sometimes desirable to quickly obtain 70 the full main pressure when long lines of hose are in use and in such cases I use the counterbalance adjustment shown in Fig. 3 in which the stirrup 12' is solid and is threaded with the hand wheel and hollow 75 nut 16 running up and down therein. When the full pressure is required the hand wheel is run up relieving the spring pressure thus obtaining the full main pressure in the outlet.

I claim:—

1. A regulator valve comprising an inlet chamber, an outlet chamber and a valve seat between the two, a cylinder above the inlet chamber, an open passage between the outlet chamber and the upper part of the cylinder, a valve stem extending through the cylinder and inlet chamber, a valve on the lower end thereof, an imperforate piston thereon within the cylinder and counterbalancing means on the upper end of the stem.

2. A regulator valve comprising an inlet chamber, an outlet chamber and a valve seat between the two, a cylinder above the inlet chamber, an open passage between the outlet chamber and the upper part of the cylinder, a valve stem extending through the cylinder and inlet chamber, a valve on the lower end thereof, an imperforate piston thereon within the cylinder, a bucket washer on the stem below the piston and counterbalancing means on the upper end of the stem.

3. A regulator valve comprising an inlet 105 chamber, an outlet chamber and a valve seat

between the two, a cylinder above the inlet chamber, an open passage between the outlet chamber and the upper part of the cylinder, a valve stem extending through the cylinder and inlet chamber, a valve on the lower end thereof, an imperforate piston thereon within the cylinder, counterbalancing means on the upper end of the stem and

means for relieving the counterbalancing pressure.

In testimony whereof I have affixed my signature in the presence of two witnesses.

JOHN J. TAGUE.
